L. T. HOUGHTON,
YARN TENSION DEVICE,
APPLICATION FILED JAN. 17, 1916.

1,344,400.

Patented June 22, 1920.

UNITED STATES PATENT OFFICE.

LEWIS T. HOUGHTON, OF WORCESTER, MASSACHUSETTS.

YARN-TENSION DEVICE.

1,344,400.

Specification of Letters Patent. Patented June 22, 1920.

Application filed January 17, 1916. Serial No. 72,435.

To all whom it may concern:

Be it known that I, LEWIS T. HOUGHTON, a citizen of the United States, residing at Worcester, in the county of Worcester and

5 State of Massachusetts, have invented a new and useful Yarn-Tension Device, of which the following is a specification.

This invention relates to a yarn tension device capable of general application, but

10 particularly designed for use in connection with the yarn guide of a spooling machine.

In this type of machine considerable difficulty has been encountered in providing an even and satisfactory tension upon the yarn,

15 such tension being necessary in order that the spools may be uniformly filled and may each contain substantially the same length of yarn. It was formerly the practice to place the bobbins loosely in inclined bobbin

20 holders or troughs within which the bobbins were revolved as the yarn was pulled sideways therefrom. It was found that this arrangement did not provide an even tension, as the pull of the yarn would frequently lift

25 the bobbins off of the supporting holders, permitting the bobbin to revolve freely in the air substantially without friction.

To avoid these defects, it is the coming practice to wind the yarn upon the bobbins 30 in the manner commonly used for winding filling, that is by depositing the yarn in short conical layers applied successively from the butt to the top of the bobbin. Such bobbins are supported in vertical position 35 and the yarn is wound off of the end of the bobbin, practically without friction.

With this arrangement, it becomes necessary and very important to provide a uniform tension upon the yarn between the 40 bobbin and the spool and a number of different devices have been devised for this purpose. All such devices of which I have any knowledge have proved defective and unsatisfactory, either through failure to provide uniform tension or on account of a 45 resulting increase in the labor of piecing up and threading the yarn.

Accordingly it is the object of my present invention to provide an improved and simplified tension device by the use of which an adequate tension may be provided without increase of labor or attention by the operator.

With this object in view, an important 55 feature of my invention relates to the provision of a tension device with which the

yarn may be brought into frictional engagement by the same movement by which it is inserted in the usual yarn guide.

Further features of my invention relate 60 to the provision of a construction by which uniform tension may be applied to the yarn and to the provision of arrangements for increasing or decreasing the tension in accordance with the conditions of use. 65

My invention further relates to certain arrangements and combinations of parts which will be hereinafter described and more particularly pointed out in the appended claims. 70

Preferred forms of my invention are shown in the drawings in which—

Figure 1 is a vertical sectional view of one form of my invention, the section being taken along the line 1—1 in Fig. 2; 75

Fig. 2 is a top plan view of the device shown in Fig. 1;

Fig. 3 is a partial front elevation thereof;

Fig. 4 is a detail perspective view of the tension member, and 80

Fig. 5 is a sectional elevation of a modification.

Referring to Fig. 1 the bobbin from which the yarn is unwound is indicated at B and the spool on which the yarn is wound is 85 marked S. A supporting bar 11 extends longitudinally of the machine, it being understood that the machine contains a large number of bobbins, spools and spindles arranged in series along each side thereof. 90 Spooler guides or snarl catchers 12 of any usual form are secured to the bar 11 by clamps 13.

My improved tension device is mounted 95 on the bar 11 and is preferably positioned on the side of the bar opposite to the spooler guide. I do not wish to be limited however to any fixed location of the device, as the device is operative over a considerable range of positions. In the form shown in Figs. 100 1 to 3, the tension device comprises a pair of parallel substantially horizontal rods 14 which are secured at one end to a clamp 15 as shown in Fig. 2. These rods may be conveniently made from a single piece of stock 105 bent to a contracted U-shape and having the free ends secured in the clamp.

A tension member 16 is supported by and 110 between the rods 14 and comprises a short cylindrical body portion 16^a, a depending hook 17 and a yarn guiding extension 18. The extension 18 first projects slightly

downwardly from the cylindrical body 16^a and then extends upwardly at an angle to the rods 14 (as clearly shown in Fig. 3).

A hanger 19 depends from the hook 17

5 and a series of weights 20 of different sizes are provided, any one or more of which may be placed upon the hanger 19 and may be thus suspended from the hook 17. One of these weights is shown in Fig. 1 and the 10 dotted lines indicate additional weights of different sizes, which may be added as desired.

15 A special yarn guide 21 is preferably provided between the bobbin B and the tension device, said yarn guide being formed with a recessed portion 21^a substantially aligned with the axis of the bobbin B and guiding the 20 yarn therefrom. The ends of the guide may be conveniently secured to the clamps 13 and 15 which clamps may of course be combined to form a single clamping member if desired.

25 The method of using the tension device is most clearly shown in Fig. 1, in which it will be seen that the yarn Y upon leaving the bobbin B passes over the yarn guide 21, over the rods 14 and 11, and beneath the tension member 16. The yarn thereafter passes through the usual guide 12 to the 30 spool S. The tension member presses the yarn downwardly so that it frictionally engages each of the supporting rods 14. As the tension upon the yarn is caused entirely by the pressure of the tension member 16 due to the weight 20 this tension will be 35 uniform during the operation of the machine and the tension upon all of the spools will be the same provided the same weights are placed upon the hangers.

40 Referring to Fig. 3, the operation of threading and inserting the yarn into the tension device and spooler guide is performed by passing the yarn by a single movement toward the left between the jaws 45 of the spooler guide. This movement will also carry the yarn along the inclined extension 18, slightly lifting the tension member until the yarn passes beneath the extension 18 and is engaged by the body member 16^a at a point between the hook 17 and the extension 18, these parts forming in effect a notch from which the yarn cannot be accidentally displaced. It will thus appear that no extra motion whatever is necessary 50 in order to place the yarn in proper position in the tension device.

55 In the carrying out of my invention it is not always essential that two extra or additional rods 14 should be provided as similar results may often be secured by providing a single rod 140 (as shown in Fig. 5), supporting the tension member 16 between itself and the bar 11. The operation of the device is essentially similar to the forms already described.

60 65 As has been noted, the tension device is

not necessarily located between the bar 11 and the bobbin, it being sufficient in most cases that the tension device is interposed between the bobbin B and the spool S.

Any usual mechanical equivalent, such as 70 a spring, may be used instead of a weight to produce pressure upon the yarn.

Having thus described my invention and certain modifications thereof it will be evident that other changes and modifications 75 can be made by those skilled in the art without departing from the spirit and scope of my invention as set forth in the claims, and I do not wish to be otherwise limited to the details herein disclosed, but what I claim 80 is:—

1. A yarn tension device comprising a pair of fixed substantially parallel yarn-guiding rods and a non-rotatable tension member supported by said rods, the yarn 85 passing over said rods and under said member and being pressed into frictional engagement between each rod and said tension member and said tension member being vertically movable to relieve excessive ten- 90 sion on the yarn.

2. A yarn tension device comprising a pair of fixed substantially parallel yarn-guiding rods and a non-rotatable tension member supported by said rods, the yarn passing 95 over said rods and under said member and being pressed into frictional engagement with each rod by said tension member, and said tension member being vertically movable to relieve excessive tension on the yarn 100 and being provided with means for supporting a selected weight thereon to increase the tension on the yarn.

3. A yarn tension device comprising a pair of substantially parallel yarn-guiding 105 rods and a tension member supported by said rods, the yarn passing over said rods and under said member and being pressed into frictional engagement with each rod by said tension member, and said tension member being vertically movable to relieve excessive tension on the yarn and having means by which the yarn may be readily guided thereunder.

4. A yarn tension device comprising a 115 pair of substantially parallel yarn-guiding rods and a tension member supported by said rods, said member overlying the yarn and pressing the yarn into contact with said rods and being vertically movable to relieve 120 excessive tension thereon, and said member being provided with means for supporting a weight thereon and also with an upwardly inclined extension by the use of which the yarn may be readily inserted beneath said 125 tension member.

5. A yarn tension device comprising a pair of substantially parallel yarn-guiding rods and a tension member supported by said rods and overlying the yarn, said mem- 130

ber having a cylindrical body portion adapted to press the yarn into frictional engagement with said rods and being freely movable longitudinally of said rods, both of 5 said rods and said member being non-rotatable.

6. A yarn tension device comprising a pair of substantially horizontal fixed rods, a non-rotatable tension member jointly supported by and on said rods and freely movable longitudinally of said rods, and means to limit said longitudinal movement and to prevent accidental displacement of said member.

10 7. A yarn tension device comprising a supporting bar, a yarn guide secured to said bar, a clamp adjustably mounted on said bar, a pair of substantially horizontal paral-

lel rods fixed in said clamp and positioned adjacent to said bar and above said guide, a 20 tension member supported by and between said rods and adapted to press the yarn into frictional engagement with said rods, and means to apply pressure to said member to increase the tension on the yarn.

25 8. A yarn tension device comprising a supporting bar, a pair of substantially horizontal parallel rods formed from a continuous piece of metal bent to contracted U-shape, means to clamp said rods to said bar 30 and a tension member supported by and between said rods.

In testimony whereof I have hereunto set my hand.

LEWIS T. HOUGHTON.
